[57] CLAIM

The ornamental design for a combined double bladed ceiling fan and illuminable lens, as shown and described.

DESCRIPTION

FIG. 1 is a perspective view of a combined double bladed ceiling fan and illuminable lens showing my new design;

FIG. 2 is a different perspective view thereof;
FIG. 3 is a side elevational view thereof, the other sides being identical to that shown; and,

FIG. 4 is a top view thereof.

The broken-line showing of a support rod in FIGS. 1-4 is for illustrative purposes only, and forms no part of the claimed design.
